(57) **CLAIM**

The ornamental design for a frame for gas cylinders, as shown and described.

DESCRIPTION

FIG. 1 is a perspective view of a design for a frame for gas cylinders.

FIG. 2 is a rear view of the design.

FIG. 3 is a front view of the design.

FIG. 4 is a left side view of the design.

FIG. 5 is a right side view of the design.

FIG. 6 is a top view of the design.

FIG. 7 is a perspective view of the design in an example environment; and,

FIG. 8 is another perspective view of the design in an example environment.

The bottom of the frame for gas cylinders is unornamented. The broken lines in FIG. 8 depict environment and form no part of the claimed design. All other broken lines depict portions of the frame for gas cylinders that form no part of the claimed design.

1 Claim, 8 Drawing Sheets
